Charles Burnham
By his Atty. J. Dennis

United States Patent Office.

CHARLES BURNHAM, OF PHILADELPHIA, PENNSYLVANIA.

Letters Patent No. 78,053, dated May 19, 1868.

IMPROVEMENT IN GAS-HEATERS.

The Schedule referred to in these Letters Patent and making part of the same.

TO ALL WHOM IT MAY CONCERN:

Be it known that I, CHARLES BURNHAM, of Philadelphia city and county, State of Pennsylvania, have invented a new and improved Adjustable Gas and Vapor-Burner; and I do hereby declare the following description and accompanying drawings are sufficient to enable any person skilled in the art or science to which it most nearly appertains to make and use my said invention or improvements without further invention or experiment.

The nature of my invention and improvements consists in providing a gas or vapor-burner composed mainly of two cylinders, the outer cylinder having a perforated disk within it, near the top, said cylinders sliding one within the other, like those of a telescope, in order to raise or lower the perforated disk or the plane of combustion, and lengthen or shorten the mixing-chamber, so as to obtain the best result in each particular case of its application.

In describing my improved burner, I refer to the accompanying drawings, forming part of this specification, of which—

Figure 1 is an elevation, and

Figure 2 a top view of the same.

A is the exterior cylinder, partially raised, and capable of being easily moved up or down upon the interior cylinder, B, the latter extending into the former in its present position, as indicated by dotted lines. The base, C, is provided with openings D D, to admit air into the mixing-chamber enclosed by the two cylinders, and the conical tube E, in the centre, is adapted to fit on an ordinary gas-burner or over any opening from which gas is to be supplied. A bead or swell, F, is formed within the outer cylinder, from about one-fourth to about one-half an inch below the upper edge, for the perforated disk, shown in fig. 2, to rest against, the position of the disk within the cylinder being shown by the dotted line at G, in fig. 1. Gas or an inflammable vapor being admitted through the tube E, it is mixed with air in the cylinders, and rising through the perforated disk, may be lighted at the top. The article to be heated being placed over it on a suitable support, the height of the disk and top of the outer cylinder containing it may be readily adjusted by moving the outer cylinder up or down upon the inner one.

The foregoing being a description of my invention, I claim, and desire to secure by Letters Patent—

The two cylinders arranged to slide telescopically, one within the other, to adjust the height of the plane of combustion or the length and capacity of the mixing-chamber, substantially as described.

CHARLES BURNHAM.
